US0D1008219S

(12) **United States Design Patent** (10) **Patent No.:** **US D1,008,219 S**
(45) **Date of Patent:** **** Dec. 19, 2023**

(54) **ILLUMINATED LOUDSPEAKER**

(71) Applicant: **Harman International Industries, Incorporated**, Northridge, CA (US)

(72) Inventor: **Hyo Jin Kim**, Shenzhen (CN)

(73) Assignee: **Harman International Industries, Incorporated**, Northridge, CA (US)

(**) Term: **15 Years**

(21) Appl. No.: **29/871,735**

(22) Filed: **Feb. 27, 2023**

Related U.S. Application Data

(63) Continuation of application No. 29/825,080, filed on Jan. 28, 2022, now Pat. No. Des. 981,371, which is a continuation of application No. 29/786,963, filed on Jun. 3, 2021, now Pat. No. Des. 944,772, which is a continuation of application No. 29/691,521, filed on May 16, 2019, now Pat. No. Des. 921,612.

(57) **CLAIM**

The ornamental design for an illuminated loudspeaker, as shown and described.

DESCRIPTION

The FIGURE is a front view of an illuminated loudspeaker, showing the new design.

The dash-dot broken lines represent the boundaries of the claimed design and form no part of the claimed design. The evenly spaced broken lines and the gray masked areas depict environment and form no part of the claimed design.
